[57] CLAIM

The ornamental design for a file housing, substantially as shown and described.

DESCRIPTION

FIG. 1 is a front elevational view of a file housing showing my new design;

FIG. 2 is an elevational view of the right side thereof;

FIG. 3 is a top plan view thereof;

FIG. 4 is an elevational view of the left side thereof;

FIG. 5 is a rear elevational view thereof; and

FIG. 6 is a bottom plan view thereof;

FIG. 7 is a front elevational view of a modified form of the file housing;

FIG. 8 is an elevational view of the right side thereof;

FIG. 9 is a top plan view thereof;

FIG. 10 is an elevational view of the left side thereof;

FIG. 11 is a rear elevational view thereof; and

FIG. 12 is a bottom plan view thereof;

FIG. 13 is a front elevational view of a further modified file housing;

FIG. 14 is an elevational view of the right side thereof;

FIG. 15 is a top plan view thereof;

FIG. 16 is an elevational view of the left side thereof;

FIG. 17 is a rear elevational view thereof; and

FIG. 18 is a bottom plan view thereof;

FIG. 19 is a front elevational view of a still further modified file housing;

FIG. 20 is an elevational view of the right side thereof;

FIG. 21 is a top plan view thereof;

FIG. 22 is an elevational view of the left side thereof;

FIG. 23 is a rear elevational view thereof; and

FIG. 24 is a bottom plan view thereof.

FIG. 1.

FIG. 2.

FIG. 3.
